UNITED STATES PATENT OFFICE.

JAMES SPEAR, OF PHILADELPHIA, PENNSYLVANIA, ASSIGNOR TO HIMSELF AND D. C. ENOS,
OF SAME PLACE.

POST-OFFICE STAMP.

Specification of Letters Patent No. 27,194, dated February 14, 1860.

To all whom it may concern:

Be it known that I, JAMES SPEAR, of the city and county of Philadelphia and State of Pennsylvania, have invented a new and 5 Improved Post-Office Stamp, for the purpose of stamping the postmark on letters and envelopes, so that the letter contained in the envelop will bear the same postmark as the envelop; and I do hereby declare that 10 the following is a full, clear, and exact description of the construction and operation of the same, reference being had to the annexed drawings, making a part of this specification, in which—

15 Figure 1, represents the stamp in a perpendicular position. Fig. 2, represents the face of the stamp. Fig. 3 represents a perspective view of one of the letters of the stamp A, the body of the type, B, the points 20 or outline of the letter, and Fig. 4 represents an impression of the stamp showing its operation.

To enable others skilled in the arts to make and use my invention I will proceed to 25 describe its construction and operation.

It is a well known fact to all business men that a large number of the letters received by them are not dated, and even do not contain the name of the State or post town 30 in which the writer resides, these important points having been omitted through carelessness or ignorance on the part of the writer, and in addition to this the post office mark is so blurred and imperfect that it is impossible 35 to tell from what town or State the letter is from, and where to send an answer. In order to prevent this evil I have constructed a stamp or die with numerous fine points which points form the outline of the 40 letter, as will be seen in Fig. 3, B, representing the points, so that when the die or stamp is pressed or struck on the letter its points

will pierce the envelop and leave the impression on the letter in a distinct manner as is shown in Fig. 4, the points and letters corresponding with each other. Another important advantage to be gained with this improved stamp is this: should the envelop be destroyed, as is done in most cases on receipt of a letter, the letter will always bear 45 the post mark in a plain and distinct manner, thus always furnishing proof as to the date and place from where it was sent.

With this improved mode of stamping letters we avoid all the objections to the present mode of stamping letters herein mentioned.

This stamp may be used with or without ink, and in order to give the stamp force enough, it may be used with a spring handle or may be placed in a frame where a lever can be used, or where a blow from the hand may send it down with sufficient force as to make a clear and distinct impression. This can be so arranged that it can be raised 65 with a spring the only force required would be to press it down on the letter. In addition to the above described purpose it may be used for other purposes where duplicate copies are required.

What I claim and wish to secure by Letters Patent is—

1. I claim constructing a stamp or die with letters the outline of which is composed of fine points constructed in the manner and for the purpose described.

2. I claim stamping letters so that the letter as well as the envelop will bear the post office mark in a distinct manner as herein described.

JAMES SPEAR.
